UNITED STATES PATENT OFFICE.

WILLIAM BEAMENDERFER, OF MOUNT JOY, PENNSYLVANIA.

TOY.

Application filed May 11, 1923. Serial No. 638,384.

To all whom it may concern:

Be it known that I, WILLIAM BEAMENDERFER, a citizen of the United States, residing at Mount Joy, in the county of Lancaster 5 and State of Pennsylvania, have invented new and useful Improvements in Toys, of which the following is a specification.

This invention relates to amusement apparatus, particularly to toys, and has for 10 its object the provision of a novel mechanical toy including two figures which travel in a circular path in and out of the representation of a barn, the first figure being pursued by the second.

15 An important and more specific object is the provision of a toy of this character in which the moving element operates automatically to open the doors in the representation of a barn, the doors reclosing by 20 spring means.

Still another object is the provision of a 25 toy of this character which embodies several novel details of construction and arrangement, which will be simple and inexpensive to manufacture, amusing and entertaining in use, efficient and durable in service and a general improvement in the art.

With the above and other objects and advantages in view the invention consists in 30 the details of construction to be hereinafter more fully described and claimed and illustrated in the accompanying drawings, in which:

Figure 1 is a plan view of the complete 35 device,

Figure 2 is a side elevation thereof,

Figure 3 is a vertical cross section,

Figure 4 is a fragmentary horizontal section taken through the representation of a 40 barn and showing the floor thereof broken away to expose the rotating arm and cams carried thereby,

Figure 5 is a detail cross section on the line 5—5 of Figure 2,

45 Figure 6 is a vertical section on the line 6—6 of Figure 3.

Referring more particularly to the drawings the numeral 10 designates the base 50 which is circular in shape and which may be constructed of any desired material, such for instance as wood. The top of this base is recessed out as indicated at 11 and at a point midway between the bottom and the upper edge is a shoulder 12. Mounted 55 upon this base and flush with the upper edge thereof is a top disk 13 of less diameter

than the recess in the base to define a circular channel or passage 14. The disk 13 is supported rigidly with respect to the base by means of a plurality of arches 15 secured to the base and the top disk and straddling the circular passage 14 for a purpose to be described.

Secured upon the disk 13 is a rectangular casing or housing 16 constructed to resemble a barn and this housing extends from one edge of the base to a point slightly beyond the center of the disk 13. At the outer corners the sides of this barn structure are provided with openings 17 normally closed by hinged doors 18 held shut by small springs 19, but capable of swinging in either direction. Projecting from each door is a depending pin 20 which projects into the passage 14 at the edge of the disk 13. This housing 16 may be painted or otherwise ornamented to resemble a barn or other out building. The disk 13 is formed at its center with a hole 21 and secured on its underside is a bearing bracket 22 within which is journaled the vertical upstanding end 23 of an arm 24 which is located beneath the disk 13 and which travels in the recess 11 of the base. The free end of this arm carries a small roller or wheel 25 which bears upon the shoulder 12 for steadyng the movement of the arm. The end of the arm 23 which projects above the disk carries a pinion 26 which constitutes one end of a train of gears 27 which form part of a 90 spring motor 28 which is located within the housing 16 and which may be of any ordinary or preferred type such as is commonly used on mechanical toys.

Carried by the free end of the arm 24 is 95 an arcuate supporting strip 30 which travels beneath the top disk and which has its ends carrying figures 31 and 32 which may of course represent anything desired. In actual practice, I prefer that the forward 100 figure 31 be the representation of a negro running and carrying a chicken, and that the figure 32 be the representation of a farmer pursuing the chicken thief. Carried by the inner edge of the strip 30 are 105 curved cams 33 and 34 which extend forwardly in advance of and rearwardly beyond the figures 31 and 32 and which are in such position as to engage the pins 20 on the doors and consequently force the doors to open position as the figures pass through the barn.

110 In the operation it will be seen that when

the spring motor is in operation, the arm 24 is rotated and the two figures carried thereby travel in a circular path around the base, the figures projecting through the channel 5 14. As the cams carried by the strip 30 engage the pins 20 on the doors, the doors will be forced open and will permit the figures to pass through the barn and out at the other side thereof, the springs on the doors 10 automatically returning them to closed position. Of course the figure of the farmer never catches the figure of the thief but the effect of a chase is very realistic and amusing.

15 While I have shown and described the preferred embodiment of the invention it is of course to be understood that I reserve the right to make such changes in the form, construction and arrangement of parts as will 20 not depart from the spirit of the invention or the scope of the subjoined claims.

I claim:

1. A toy of the character described comprising a supporting base having a recess 25 therein leading into a circular passage at the top of the base, a housing mounted above the base and extending across the passage, said housing being formed at opposite sides with doorways normally closed by hinged 30 doors held shut by spring means, a rotary arm traveling within the recess and journaled at the center of the base, a member carried by said arm, figures mounted on said member and operating arms carried by the 35 doors and disposed in the path of said member whereby the member will engage and open the doors upon the approach of said figures thereto.

2. A toy of the character described comprising a supporting base having a recess 40 therein leading into a circular passage at the top of the base, a housing mounted above the base and extending across the passage, said housing being formed at opposite sides 45 with doorways normally closed by hinged doors held shut by spring means, a rotary arm traveling within the recess and journaled at the center of the base, an elongated member carried by the free end of said arm, figures supported upon said member and arranged one behind the other and means car-

ried by the doors and engageable by said member for effecting opening of the former upon the approach of the figures.

3. A toy of the character described comprising a supporting base having a recess therein leading into a circular passage at the top of the base, a housing mounted above the base and extending across the passage, said housing being formed at opposite sides with 55 doorways normally closed by hinged doors held shut by spring means, a rotary arm traveling within the recess and journaled at the center of the base, figures carried by the outer end of said arm and traveling along 60 said passage, said doors being provided with projections extending down into the passage, and curved cams on said arms extending to the front and rear of the figures 65 thereon and engageable with said projections to effect opening of the doors.

4. A device of the character described comprising a base having a recess and a shoulder therein, a top disk secured above the base in spaced relation to the wall of 75 the recess to define a circular passage, an arm having one end upturned and journaled through said top disk, said arm being rotatable within said recess and carrying figures projecting up through said passage, a housing mounted upon the disk and extending across the passage, drive means within said housing for rotating said arm, said housing being formed at opposite sides with spring 80 hinged doors, and means on said arm at said figures for engagement with said doors to effect opening thereof.

5. In a device of the character described, a hollow base having a circular slot therein, a housing mounted on the base and having 90 door ways above said slot, spring pressed doors normally closing said door ways, projections carried by the doors, a rotary arm pivoted within the center of the base, a motor mechanism for rotating the arm, a pair 95 of figures supported from the arm and traveling along said slot, and cam means on the arm engageable with said projections for opening the doors.

In testimony whereof I affix my signature.

WILLIAM BEAMENDERFER.
